Howard P. Denison
ATTORNEY

UNITED STATES PATENT OFFICE.

FRANK A. VAIL, OF AUBURN, NEW YORK.

SECTIONAL BRAKE-BAND LINING.

Application filed June 1, 1922. Serial No. 565,118.

To all whom it may concern.:

Be it known that I, FRANK A. VAIL, a citizen of the United States of America, of Auburn, in the county of Cayuga, in the 5 State of New York, have invented new and useful Improvements in a Sectional Brake-Band Lining, of which the following, taken in connection with the accompanying drawings, is a full, clear, and exact description.

10 This invention relates to a sectional brake-band lining and refers more particularly to the means for fastening the sections to the band, the object being to provide means whereby the worn sections may be removed 15 individually and replaced by new ones without removing the band from the brake drum.

In other words, I have sought to provide a lining in the form of relatively short sections mounted upon a suitable supporting plate so that they may be manufactured 20 in units and assembled in the brake-band without other fastening means than the mere wedging engagement with keepers on the band and bendable tongues adapted to be 25 bent around one edge of the band at the smaller edge of the wedge plates, thus permitting any one of the worn sections to be removed and replaced by new ones independently of the other sections.

30 Other objects and uses will be brought out in the following description:

In the drawings:

Figure 1 is a longitudinal sectional view of a portion of a brake-band equipped with 35 my improved sectional lining.

Figure 2 is an inner face view of a portion of the same brake-band showing the manner of fastening the sections thereto.

Figure 3 is a transverse sectional view 40 taken on line 3-3, Figure 2.

The brake-band as 1— preferably consists of a flat strip of sheet metal bent into circular form of nearly circumferential length of the revoluble drum with which 45 it is adapted to cooperate for braking purposes and is carried by a bracket 2— adapted to be secured to some stationary part of the machine upon which the brake drum is mounted and is also provided with 50 a lug 3— for attachment to an expanding and contracting device not shown, but commonly used with expansible and contractible brake-bands of this character.

A series of relatively short keeper plates 55 4— are secured by rivets 5— to the

inner face of the brake-band preferably in uniform longitudinally spaced relation to extend from edge to edge of the band, each keeper plate being wedge-shaped or rather having its opposite edges tapered or converging in one direction transversely of the band and provided with grooves 6— adjacent the inner faces of the band, thereby forming flanges 7— at the inner sides of the grooves and also tapered in the same 65 direction.

The lining for engaging the brake drum preferably consists of a series of sections 8— alternating with the keepers 4— and of substantially the same cylindrical 70 length as the distance between adjacent keepers, each section comprising a metal locking plate 9— and a friction plate 10— of any suitable material secured by rivets 11— to the locking plate 9—. 75

The spaces between the keeper plates 4— is somewhat greater than the circumferential width of said keeper plates and therefore, the locking plates 9— are of greater length than the corresponding 80 length of the keeper plates.

The opposite ends of the locking plates 9— extend short distances beyond the corresponding ends of the adjacent friction plate 10— so as to project into the grooves 85 6— of the adjacent keeper plates 4— and are also wedge-shaped or tapered transversely of the band to conform to the taper of the opposite edges of said keeper plates.

That is, the opposite edges of the keeper 90 plates are tapered transversely in one direction while the opposite ends of the locking plates are tapered transversely in the opposite direction so as to wedge against the adjacent edges of the keeper plates in the 95 grooves 6— when inserted in operative position whereby the flanges 7— serve to hold the locking plates against inward displacement while the outer faces of the locking plates rest against the inner face of the 100 band 1—.

The shorter longitudinal edge of each locking plate 9— is provided with a plurality of bendable tongues 12—, which normally stand out straight from the plate 105 when the latter is being inserted between the keeper plates 4— and extend beyond the corresponding edge of the brake band across and under which they are bent as shown in Figure 2 to hold the locking plates against 110

lateral displacement in one direction, while the wedge-shaped edges cooperating with the keeper plates —4— serve to hold the liner sections against displacement in the opposite site direction.

For example, in placing any one of the liner sections in operative position upon the inner face of the brake-band —1—, the opposite ends of the plate —9— are registered 10 with the grooves —6— in the adjacent keeper plates —4— and then the entire section is driven tightly into place with the wedging fit against the keeper plates after 15 which the tongues —12— are bent outwardly around the adjacent edge of the band —1— to clinch the sections in operative position.

In order to remove any one of the sections, its tongues —12— are rebent by a suitable chisel or pliers to their straightened position as 20 shown by dotted lines in Figure 3 whereupon the section may be driven laterally out of wedging engagement with the adjacent keeper plates to permit the reinsertion of the new section if desired in the manner previously described.

What I claim is:—

1. The combination with a brake-band, keeper plates secured to the inner face of the brake-band in circumferentially spaced 30 relation, and liner sections inserted between and against adjacent keeper sections and also against the inner face of the brake-band and provided with tongues bent across and against one edge of the band.

2. In combination with a brake-band, keeper plates secured to the inner face of the brake-band in circumferentially spaced relation and having their opposite longitudinal edges tapered in one direction, and 40 liner sections seated on the inner face of the band between the keeper sections and having their opposite ends tapered in the opposite

directions from those of the keeper plates for wedging engagement therewith.

3. In combination with a brake-band, 45 keeper plates secured to the inner face of the brake-band in circumferentially spaced relation and having their opposite longitudinal edges tapered in one direction, and liner sections seated on the inner face of the band 50 between the keeper sections and having their opposite ends tapered in the opposite directions from those of the keeper plates for wedging engagement therewith, said keeper plates having flanges overlapping upon the 55 adjacent ends of the liner sections.

4. In combination with a brake-band, keeper plates secured to the inner face of the brake-band in circumferentially spaced 60 relation and having their opposite longitudinal edges tapered in one direction, and liner sections seated on the inner face of the band between the keeper sections and having their opposite ends tapered in the opposite 65 directions from those of the keeper plates for wedging engagement therewith, the smaller ends of the liner sections being provided with bendable tongues bent over and upon the adjacent edge of the band.

5. The combination with a brake-band 70 having transversely tapered abutments in circumferentially spaced relation, and transversely tapered liner plates wedging between adjacent abutments and provided with bendable tongues at their smaller ends 75 bent over and upon the adjacent edge of the band.

In witness whereof I have hereunto set my hand this 22nd day of May, 1922.

FRANK A. VAIL.
